SAFETY RAZOR COMBINED WITH BLADE
CONDITIONING MEANS

Godfrey Thornfield, London, England

Application December 9, 1943, Serial No. 513,537
In Great Britain November 27, 1942Section 1, Public Law 690, August 8, 1946
Patent expires November 27, 1962

15 Claims. (Cl. 30—34)

1

This invention relates to safety razors and has for its object the provision of improved means whereby, without using the usual stropping or sharpening devices, the blade of a safety razor may be maintained in good condition for a long period of use.

The invention comprises the incorporation of a stropping or a sharpening surface in the structure of the safety razor itself.

In order that the invention may be the more clearly understood, a number of constructions in accordance therewith as applied to razors of the "Gillette" type will now be described, reference being made to the accompanying drawings, wherein—

Figure 1 is a side elevation, shown mainly in section, of one of said constructions, with the parts in the condition for stropping the blade;

Figure 2 is a section on line 2—2 of Figure 1;

Figure 3 is a section on line 3—3 of Figure 1;

Figure 4 is a plan of the base member of the razor;

Figure 5 is a plan of the blade;

Figure 6 is an under plan of the clamping member of the razor;

Figure 7 is a sectional side elevation of another construction, with the parts in the condition for stropping;

Figure 8 is a section on line 8—8 of Figure 7;

Figure 9 is a central section looking from the left of Figure 1 but with the parts in the clamped condition for shaving.

Figure 10 is a plan of the same shown in section through the handle;

Figure 11 is an under plan of the clamping member of the razor;

Figure 12 is a side elevation shown mainly in section of another construction, with the parts in the condition for stropping;

Figure 13 is a side elevation looking from the left to Figure 12 and shown in section on line 13—13 of Figure 12;

Figure 14 is a similar view to Figure 13 but with the parts in the clamped condition for shaving;

Figure 15 is a plan of Figure 12 shown in section through the handle;

Figure 16 is a section on line 16—16 of Figure 15.

Describing first the construction shown in Figures 1 to 6, this construction is a razor of the "Gillette" type comprising in the usual way a base member 1 whose under surface is adapted to engage the skin being shaved and against whose upper surface, with its two edges pro-

2

jecting, the blade 2 is adapted to be clamped by means of a clamping member 3 whose edges project beyond the edges of the blade. Thus, in shaving, the cheek is, in the usual way, engaged by the under surface of the base member 1, and also by the narrow edge portions of the blade 2, which project beyond the edges of said base member, and the two marginal portions of the clamping member 3, which project beyond the edges of the blade. In the usual way the upper surface of the base member 1 is concave and the lower surface of the clamping member 3 is convex so that the blade is flexed to curved form when the clamping member is pressed down. In Figures 1 and 2 the clamping member 3 is shown not pressed down and the blade 2 is accordingly straight as will hereinafter appear. In the usual way locating lugs 4 on the upper surface of the base member 1 engage in openings 5 in the blade 2 and also in recesses 6 in the under surface of the clamping member 3 when the latter is clamped down.

In the present arrangement the under surface of the clamping member 3 carries a pad 7 of chamois leather or the like impregnated with petroleum jelly or the like, and the base member 1 carries on its upper side a flat spring plate 8 whose upper surface also has mounted thereon a pad 9 of chamois leather or the like impregnated with petroleum jelly or the like. When the clamping member 3 is at the down or clamping position (not shown) this plate 8 together with the pad 9 is flexed with the blade, but when the clamping member is at the position shown in Figures 1 and 2, said plate 8 and pad 9 straighten out as shown and the pad maintains contact with the blade which also straightens. When the blade 2 is at the straight position shown in Figures 1 and 2 it is clear of the locating lugs 4, and, in the present arrangement means are provided whereby the clamping member 3 can be lifted to the position shown in Figures 1 and 2 and whereby the blade 2 can then be rotated to and fro about its centre. When this is done the two surfaces of the blade are respectively rubbed against the two pads 7 and 9 and the blade is accordingly stropped and the petroleum jelly will be transferred to the blade for repelling the water from the blade surface. After shaving therefore, all that is necessary to do to prevent rusting of the blade is to lift the clamping member 3 to the position shown and oscillate the blade 2 as stated after which the clamping member can be again clamped down and the razor put away ready for its next use.

Describing now the mechanism by which this clamping member 3 can be lowered and raised and by which the blade 2 can be oscillated when said clamping member is raised, the base member 1 has a central screwed stud 10 projecting upwardly from it on which the plate 8, pad 9, blade 2 and clamping member 3 are impaled, and the handle 11 screws on this stud for keeping the parts assembled. Said handle 11 has a sleeve 12 rotatably located on its bottom portion as shown and this sleeve 12 has rigidly mounted on its bottom end a disc 13 which is adapted to fit freely in a recess in the upper surface of the clamping member 3. The sleeve 12, at its upper end, abuts against a milled nut 14 which is in screwed relation on the handle 11. With the handle 11 screwed fully down on to the stud 10, if the nut 14 is screwed down towards the lower limit of its travel on the handle 11, the bottom end of the sleeve 12 and the disc 13 will press the clamping member 3 to the down or shaving position and if said nut 14 is screwed up towards its upper limit as shown, the bottom of the sleeve 12 and the disc 13 will permit the blade 2 and plate and pad 8 and 9 to straighten to the position shown in Figures 1 and 2.

For oscillating the blade 2 when the parts are at this position shown, a pin 15 is provided mounted on, and depending downwardly from, the disc 13. This pin passes through an arcuate slot 16 in the clamping member 3 and through one of the slots 5 of the blade 2 as shown, near the inner end and clear of the adjacent lug 4. The arcuate slot 16 is concentric with the stud 10 and extends through 180°. Thus, when the clamping member 3 is at the up position shown, the sleeve 12 (which is milled) and therefore the disc 13 and pin 15 can be oscillated through 180° about the axis of the handle 11 and this oscillates the blade 2 through the same angle. The spring 8 with its pad 9, and also the clamping member 3 are prevented from rotating with the blade 2 by virtue of the fact that the lower portion 17 of the stud 10 is of square section and engages in square holes 18 and 19 in the plate 8 and pad 9 and the clamping member 3. The central hole 20 of the blade is sufficiently large to rotate around the square portion of the pin.

Ordinarily therefore the handle 11 is kept fully down on the stud 10. When the razor is to be used the nut 14 is screwed down until the clamping member 3 clamps the blade at the correct setting and when the blade is to be stropped the nut 14 is screwed upwards to the right position and the sleeve 12 is oscillated thereby drying and stropping the blade as stated. The nut 14 is then screwed down again ready for the next shave and the razor is put away. The handle 11 only has to be unscrewed when the razor is to be disassembled say for renewing the blade.

It will be noted that the arcuate slot 16 is so located that the blade is oscillated on either side of a mid position at right angles to the base member and clamping member.

Describing now the construction shown in Figures 7 to 11, this construction as in the preceding construction comprises a base member 1, a blade 2, a clamping member 3', and studs 4 on the upper surface of the base member engaging in openings 5 in the blade and in recesses 6 in the clamping member.

Also, as in said preceding construction, the base member 1 has the usual central screwed stud 10' on which the blade 2 and clamping member 3' are impaled and the handle 11' screws

on to this stud for keeping the parts assembled. It will be seen that the lower end of the handle 11' in this case passes through the member 3' and blade 2 and rests flush against the base member 1.

The clamping member 3' also has a pad 7 (shown in two parts) on its under surface, but the plate 8 and pad 9 of the preceding construction are dispensed with. When the razor is to be dried and stropped, the clamping member 3' is raised from the clamping position shown in Figure 9 to the position shown in Figure 8 at which the blade 2 is straight, and, the blade 2 remaining stationary, said clamping member 3' is turned through a right angle about the axis of the stud 10', and, holding the ends of the base member and blade between the thumb and finger of say the left hand, and the ends of the clamping member 3' between the thumb and finger of the right hand, said clamping member is oscillated about the axis of the handle with its under surface pressed against the surface of the blade. The arrangement for locating the blade during this operation may be either as shown in the left hand part of Figure 7, or as shown in the right hand part of Figure 7. According to the left hand part the locating studs 4 are just high enough to locate the blade while not projecting substantially above its surface. According to the right hand part of the figure additional studs 21 are provided engaging holes near the centre of the blade, and the clamping member is formed with an annular recess 22 which leaves it free to rotate clear of said studs 21.

When one side of the blade is stropped and dried the razor is disassembled and then reassembled with the blade reversed, and the other side of the blade is then stropped and dried. The clamping member 3' is then clamped down to the position of Figure 9 and the razor is ready for the next shave.

In the present construction, the means for permitting the clamping member 3' to rise to the position of Figure 8 for stropping consist of a collar 23 in screwed relation on the handle 11' and bearing at its lower end in a recess in the upper surface of the clamping member 3'. With the handle 11' screwed fully down as shown, the clamping member 3' will be either at the clamping position of Figure 9 or at the up position of Figure 8 according to whether the collar 23 is screwed down or up. For disassembling the razor the handle 11', with the collar 23 on it, is of course completely unscrewed from the stud 10'.

In this construction means are also provided to enable the blade to be sharpened when this becomes necessary after a long period of use. Thus carborundum or other sharpening material 24 is inset flush in the upper surface of the clamping member 3' in longitudinal strips near the side edges thereof. To sharpen the blade the whole razor is disassembled and the blade 2 is laid longitudinally on the upper surface of the clamping member and is longitudinally reciprocated while being pressed gently down by the fingers on said surface. Its edges will lie over the carborundum insets 24 and satisfactory sharpening will be effected.

To make place for the carborundum insets the usual longitudinal slots through the clamping member 3' at the sides thereof are inclined as best shown in Figure 8.

Describing now the construction shown in Fig-

tures 12 to 16, this construction is somewhat similar to that of Figures 1 to 6, but, instead of the blade being capable of oscillation through 180° only, it is capable of being continuously rotated.

Thus this construction, like that of Figures 1 to 6, comprises a base member 1, a blade 2, adapted to be clamped down on the base member by a clamping member 3", and locating studs 4 on the base member which engage in openings 5 in the blade and also in recesses 6 in the under surface of the clamping member when the latter is clamped down. Also as in Figures 1 to 6 the under surface of the clamping member carries a pad 7 and the base member carries a spring 8 and pad 9. Also, as in Figures 1 to 6, means are provided whereby the clamping member 3" can be lifted to the position shown in Figures 12, 13 and 16, but, in the present arrangement, when the clamping member is lifted to this position the blade can be continuously rotated, instead of oscillated, for stropping and drying the blade.

Describing now the mechanism by which the clamping member 3" can be lowered and raised, and by which the blade 2 can be rotated when said clamping member is raised, the base member 1 has a central screwed stud 10" projecting upwardly from it on which, as before, the plate 8, pad 9, blade 2 and clamping member are impaled, and the handle 11" screws on this stud for keeping the parts assembled. Said handle 11" has a sleeve 12a surrounding its bottom portion as shown, and this sleeve is rigidly fixed to the clamping member 3" by means of a bridging piece 3a which is integral with said clamping member 3". The lower end of the sleeve 12a fits over a square section portion 25 of the stud 10" just beneath the screw threaded portion and this prevents rotation of said sleeve, and therefore of the clamping member 3", relative to the base member 1. The sleeve 12a, at its upper end, abuts against a milled nut 14 in screwed relation on the handle 11", and, as in the case of Figures 1 to 6, by screwing this nut up and down the clamping member is raised to the stropping position of Figures 12, 13 and 16 or lowered to the clamping position of Figure 14.

Said clamping member 3" comprises a circular central portion 3b which is rotatable relative to the main portion 3". This portion 3b, which is located in an opening in the main portion 3" and under the bridging piece 3a as shown, bears on a circular section portion 26 of the stud 10 just beneath the square section portion 25. The under surface of this central portion 3b conforms to the general convex shape of the clamping member as shown, and said central portion has lugs 3c (Figure 12) extending down from its under surface which engage with slots in the blade. When the clamping member is raised to the up position of Figures 12, 13 and 16, this central portion (which is formed with a bevelled milled edge as shown) can be rotated by the fingers and will thereby rotate the blade 2, and thus the blade will be dried on both sides as in the case of Figures 1 to 6, without the limitation that it can only be oscillated through 180°.

In each of the constructions heretofore described, a small cylinder or plug 27 of solid petroleum jelly or the like is contained in the outer end of the bore of the handle 11. This plug 27 is carried by a closing cap 28, and by unscrewing this cap the plug can be removed and rubbed on the pads 7 and 9 thereby re-impregnating them when they begin to dry.

What I claim and desire to secure by Letters Patent is:

1. A safety razor of the Gillette type comprising a base element, a blade, and a clamping element by which the blade is clamped down on the base element, said clamping element having disposed on its under side a relatively soft, porous member impregnated with grease-like water repellent for transferring said water repellent to the razor blade.

2. A safety razor of the Gillette type comprising a base element, a blade, and a clamping element by which the blade is clamped down on the base element, said clamping element having disposed on its under side a relatively soft, porous member impregnated with grease-like water repellent for transferring said water repellent to the razor blade and said base element carrying on the upper side thereof a relatively soft, porous member impregnated with a grease-like water repellent.

3. A safety razor according to claim 2 comprising means for lifting the clamping element from the clamping position to a limiting position at which the blade is straight and held lightly between the two members carrying a grease-like water repellent, and means for rotating the blade when thus held thereby simultaneously applying water repellent material to both surfaces of said blade.

4. A safety razor of the Gillette type comprising a base element, a blade, a clamping element by which the blade is clamped down on the base element, a spring plate mounted on top of the base plate, said clamping element having the underside thereof and said spring plate on the upper side thereof a surface adapted to condition said razor blade, said spring plate and said blade straightening together upon release of pressure.

5. In a safety razor of the Gillette type comprising a base element, a blade, and a clamping element by which the blade is clamped down on the base element, said clamping element having disposed on its under side a surface adapted to condition the razor blade, and said base element having a blade conditioning surface on the upper side thereof, in combination, a screw threaded handle, a correspondingly threaded means on said base element adapted to cooperate with said handle to keep the base, the blade and the clamping element assembled, a nut on said handle axially adjustable thereto, for advancing said clamping element into blade clamping position or for retracting it into a position leaving the blade free for rotation between said conditioning surfaces, a sleeve rotatable on said handle, said sleeve being interposed between said nut and said clamping element, which sleeve holds the clamping element down, a pin supported by the bottom end of said sleeve, said pin being capable of engaging in a hole of said blade and of passing through an arcuate slot in said clamping element thereby effecting rotation of the razor blade for conditioning the same when the sleeve is rotated.

6. In a safety razor of the Gillette type comprising a base element, a blade, and a clamping element by which the blade is clamped down on the base element, said clamping element having disposed on its under side a surface adapted to condition the razor blade, and said base element having a blade conditioning surface on the upper side thereof, in combination, a screw threaded handle, a correspondingly threaded means on said base element adapted to cooperate with said

handle to keep the base, the blade, and the clamping element assembled, a nut on said handle axially adjustable thereto, for advancing said clamping element into blade clamping position or for retracting it into a position leaving the blade free for rotation between said stropping and drying surfaces, a spacing sleeve between said nut and said clamping element, said sleeve being connected at its lower end to the clamping element and bears with its upper end against said nut whereby said clamping element is held down, a central insert rotatably received in an opening in said clamping element, said insert having at least one pin or stud extending downwardly therefrom for engaging in openings in said blade, whereby rotation of said insert effects rotation of said blade.

7. A safety razor according to claim 6, wherein in the under surface of said rotatable insert is curved to conform to the shape of the clamping element, whereby said insert forms in effect a part of said clamping element.

8. A safety razor according to claim 6, wherein said clamping element carries a bridging piece, said spacing sleeve being connected at its lower end to said bridging piece and said rotatable insert being located underneath said bridging piece and being exposed at the two sides of said bridging piece, whereby said insert can be rotated by the fingers.

9. In a safety razor of the Gillette type comprising a base element, a blade and a clamping element by which the blade is clamped down on the base element, said clamping element having disposed on its under side a surface adapted to recondition the razor blade, in combination; a screw threaded handle, a correspondingly threaded means on said base element adapted to operate with said handle to keep the base, the blade and the clamping element assembled, and means on said handle axially adjustable thereto, for advancing said clamping element into blade clamping position or for retracting it into a position in which it is free to rotate for blade reconditioning, means for rotating said clamping element when so positioned, and means for holding the blade against rotation while the clamping element is so rotated.

10. A safety razor comprising a base member and an upper member between which the blade is adapted to be clamped, a handle screw-connected to said base member, an adjusting element mounted on said handle and serving to hold said upper member down at the clamping position relative to said base member, whereby said blade is pressed to curved form, and a blade-conditioning element mounted on one of said members contiguous to the blade, said adjusting element being axially adjustable relative to said handle to permit said upper member to lift and said blade to spring to its flat state, while said handle is fully screw-connected to said base member, and relative rotation between said blade and said blade-conditioning element being thereafter permissible about the axis of said handle, whereby said blade is conditioned by said blade-conditioning element.

11. A safety razor comprising a base member and an upper member between which the blade is adapted to be clamped, a handle screw-connected to said base member, an adjusting element mounted on said handle and serving to hold said upper member down at the clamping position relative to said base member, whereby said blade is pressed to curved form, and a blade-condi-

tioning element mounted on both of said members contiguous to the blade, said adjusting element being axially adjustable relative to said handle to permit said upper member to lift and said blade to spring to its flat state, while said handle is fully screw-connected to said base member, and relative rotation between said blade and said blade-conditioning element being thereafter permissible about the axis of said handle, whereby said blade is conditioned by said blade-conditioning element.

12. A safety razor comprising a base member with a concave upper surface and an upper member with a convex lower surface, a spring plate mounted on the upper side of said base member, a blade conditioning element mounted on the upper side of said spring plate, a handle adapted to be screw-connected to said base member and thereby to hold said upper member down at the clamping position relative to said base member with the blade between said upper member and said blade-conditioning element, whereby said blade and said spring plate are bent to curved form conforming to the concave and convex surfaces of said base member and said upper member, means whereby said upper member may be permitted to lift relative to said base member, thereby permitting said blade and said spring plate to spring to their flat state, whereupon rotation of said blade relative to said base member is permissible about the axis of said handle, whereby said blade is conditioned by said blade-conditioning element.

13. A safety razor comprising a base member with a concave upper surface and an upper member with a convex lower surface, a spring plate mounted on the upper side of said base member, a blade conditioning element mounted on the upper side of said spring plate and another blade-conditioning element mounted on the lower surface of the upper member, a handle adapted to be screw-connected to said base member and thereby to hold said upper member down at the clamping position relative to said base member with the blade between said upper and said lower blade-conditioning elements, whereby said blade and said spring plate are bent to curved form conforming to the concave and convex surfaces of said base member and said upper member, means whereby said upper member may be permitted to lift relative to said base member, thereby permitting said blade and said spring plate to spring to their flat state, whereupon rotation of said blade relative to said base member is permissible about the axis of said handle, whereby said blade is conditioned by said blade-conditioning elements.

14. A safety razor comprising a base member having a curved surface and an upper member having a curved surface complementary to the first mentioned curved surface, a blade-conditioning element mounted on the underside of said upper member, a handle adapted to be screw-connected to said base member and thereby to hold said upper member down at the clamping position relative to said base member, with the blade between said blade-conditioning element and said base member whereby said blade is bent to curved form, and means for lifting said upper member relative to said base member, thereby permitting said blade to spring to its flat state, and for rotating said upper member about the axis of said handle while the blade remains stationary on said base member, whereby said blade is conditioned by said blade-conditioning element.

15. A safety razor comprising a structure for holding a razor blade for shaving, said structure including a base member and a clamp member between which the blade is adapted to be held by clamping action; and means associated with said structure for conditioning the blade against rusting while the blade is carried by the structure, said means including two pieces of chamois leather, or the like, impregnated with a water repellent material, said pieces being carried between the confronting faces of the base and clamp members, one of said pieces being disposed on one side of the blade and the other piece being disposed on the opposite side of the blade, said water repellent material being transferable from said pieces to the blade by contact with the blade.
